VALVE TOOL

Ira J. Clark, Fort Morgan, Colo.

Application November 30, 1936, Serial No. 113,403

4 Claims. (Cl. 81—3)

The valve springs in a modern internal combustion engine are held in place by means of small wedge-shaped split cones which are positioned around the valve stem. These split cones have internal ridges which engage grooves in the stem to prevent longitudinal movement of the cones. The valve spring washer prevents separation of the cones so that when the latter are in place, the valve spring is securely locked in position on the valve stem.

This invention relates to a tool for placing these split cone valve spring retainers in position on the valve stem.

The principal object of the invention is to provide a highly efficient tool, which will securely hold the two halves of the retaining cone while the latter are being placed in position; which will operate in the very limited space provided between the valve retaining washer and the valve tappet; which will provide a permanent bottom for holding the cones in the tool which after the cones are in place, can be slipped from under them to allow the valve spring to reach its bottommost position; and which will retain its grip on the cones until they are completely enclosed by the valve spring retaining washer.

Other objects of the invention and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:—

Fig. 1 is a perspective view illustrating the split cones being positioned in the tool.

Fig. 2 is a similar view illustrating the use of the tool in placing the cones about the valve stem.

Fig. 3 is a side elevation of the tool as it appears as the spring is lowered in place on the valve stem.

Fig. 4 is a plan view of the tool being released from the cones after the latter are in position in the spring retaining washer.

Fig. 5 is a plan view of the tool handle and sleeve taken on the line 5—5, Fig. 3.

In the drawing a typical valve stem of the type employed on internal combustion engines is indicated at 10, a valve spring 11, spring retaining washer at 12, valve tappet 13, and split cones at

22. In Fig. 2, the valve spring is shown supported and compressed by a valve spring compressing tool 14.

The invention comprises a handle member 15 having a channel plate 17 slidably mounted thereon. The channel plate 17 may be projected forwardly or withdrawn by means of the user's thumb. The movement of the channel plate is limited by a rivet 18 which passes through a slotted hole 25 in the channel plate 17. The forward extremity of the channel plate is bifurcated as shown at 27 so that it will pass on each side of the valve stem 10 when in the projected position.

A pair of spring actuated jaws 19 are mounted upon a pivot rivet 20 extending from the handle 15 through a slotted opening 26 in the channel plate 17. The jaws 19 are forced apart at their rearward extremities by means of a coil spring around their pivot pin 20, as is usual in such constructions. The extremity of the spring shows inside the rearward extremity of the upper jaw 19 in Fig. 2. The forward extremities of the jaws 19 are conically indented as shown at 21 to conform to the shape of the usual split cone 22.

A separating bar 23 extends forwardly between the two jaws 19. This bar is held in place by the rivets 18 and 20, and is longitudinally slotted as shown at 24 so that it may move forwardly and back over these rivets. The forward extremity of the separating bar is provided with a concavity or notch 16.

In use, the operator forces the separating bar 23 between the two spring actuated jaws 19. He then individually separates the jaws from the bar by the pressure of his thumb and slips the cones 22 in place in the sockets 21 of the jaws, as shown in Fig. 1.

It is desired to call attention to the fact that at this time, the channel plate 17 is in its forward position so that it provides a firm bottom for the support of the cones 22 in the jaws. The incline of the cones prevents them from moving upwardly in the jaws and the channel plate 17 prevents them from moving downwardly so that the cones are firmly held and absolutely prevented from falling from the tool. He now compresses the valve spring by means of the compressor 14 and presses the notched extremity 16 of the separating bar 23 against the valve stem 10 at the point where the latter is grooved to receive the cones. As the tool is pushed inwardly, the separating bar will travel backwardly and will move out of position between the

cones as the valve stem moves into position therebetween.

The cones are now adjusted until their ridges reach and engage the grooves in the valve stem 5 10. This allows the jaws to close and causes them to snap the separating bar 23 rearwardly. The channel plate 17 is now withdrawn by the user's thumb, as shown in Fig. 3, so that there is nothing below the cones on the valve stem. The 10 spring compressing tool 14 is now released to lower the spring and, as the spring lowers, the jaws are forced downwardly over the cones to allow the retaining washer 12 to take their place.

Since there is no part of the tool below the 15 cones, the tool can move downwardly completely to and over the valve tappet 13, if necessary, without interference with the expansion of the spring 11 and without releasing the cones. The operator then engages the rear extremities of the 20 jaws 19 with his fingers so as to separate them and release them, as shown in Fig. 4.

While a specific form of the improvement has been described and illustrated herein, it is desired to be understood that the same may be varied, 25 within the scope of the appended claims, without departing from the spirit of the invention.

Having thus described the invention, what is claimed and desired secured by Letters Patent is:—

30 1. A split cone tool for engine valve work comprising: a handle member; a pair of spring actuated jaws secured to said handle member, each of said jaws being provided with a socket for receiving a split cone; a channel member fitted 35 over the top and edges of said handle between the latter and said jaws to maintain said cones in the sockets in said jaws, said channel member being longitudinally slidable on said handle member so that it may be withdrawn from said cones 40 when the latter are in place.

2. A split cone valve tool comprising: a handle member; a pivot member extending from the

upper face of said handle member; a pair of spring-actuated jaws mounted on said pivot member and extending beyond the extremity of said handle member, each of said jaws being indented to receive a split cone; a separating bar 5 slidable between said jaws, said bar having an elongated hole for the passage of said pivot member; and a slidable plate positioned between said jaws and said handle member to maintain the split cones in said indentations. 10

3. A split cone valve tool comprising: a handle member; a pivot member extending from the upper face of said handle member; a pair of spring-actuated jaws mounted on said pivot member and extending beyond the extremity of 15 said handle member, each of said jaws being indented to receive a split cone; a separating bar slidable between said jaws, said bar having an elongated hole for the passage of said pivot member; an aligning member projecting from said handle member through a slotted hole in said separating member to hold the latter in alignment with said handle member; and a slidable plate positioned between said jaws and said handle member to maintain the split cones in 20 place in said indentations, said plate being slotted for the passage of said pivot member and said aligning member. 25

4. A split cone valve tool comprising: a handle member; a pivot member extending from the upper face of said handle member; a pair of spring-actuated jaws mounted on said pivot member and extending beyond the extremity of 30 said handle member, each of said jaws being indented to receive a split cone; a separating bar slidable between said jaws; and a slidable plate positioned between said jaws and said handle member to maintain the split cones in 35 said indentations.
